(57) **CLAIM**

The ornamental design for a mobile phone case, as shown and described.

DESCRIPTION

FIG. 1 is a front, right and top perspective view of a mobile phone case, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another rear, left and top perspective view of the mobile phone case in another state; and,

FIG. 10 is another rear, left and top perspective view of the mobile phone case in another state.

The broken lines depict portions of the mobile phone case that form no part of the claimed design.

1 Claim, 10 Drawing Sheets
